Primary Examiner — Cynthia Ramirez*Assistant Examiner* — Michael A Maharajh(74) *Attorney, Agent, or Firm* — Olav M. Underdal; IDP Patent Services(57) **CLAIM**

The ornamental design for a massage roller, as shown and described.

DESCRIPTION

FIG. 1 is a front perspective view of a massage roller showing my new design;

FIG. 2 is a rear perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The broken lines show unclaimed portions of the massage roller only and form no part of the claimed design.

1 Claim, 8 Drawing Sheets
